WINDOW OPENING DEVICE

Ottmar Stotz, 1504 Washington St., Evanston, Ill.
Filed Dec. 16, 1959, Ser. No. 859,988
3 Claims. (Cl. 268—117)

This invention relates to a mechanical window operator and more particularly to a variable position window operator for a casement window having provision to be readily installed on presently existing casement window constructions.

There are in present use a few varieties of casement window operating devices. Nearly all that are used commercially require the window frame installation to have special provision to accommodate the operator. The above types are unable to provide the advantages of a device which is completely adaptable to all types of casement constructions, being compact and placing virtually no limit on space requirements. Furthermore, the existing operators lack a high degree of ease in hand operation and require extra manual adjustments to lock the window in a desired position.

The above problems are obviated by providing a casement window operator having a flexible coilable tongue member composed of spring metal which is connected to the window by a particularly constructed connector. The tongue member is transversely arched to afford rigidity when extended linearly outward to push or pull the window. The tongue member is driven by a hand crank and transmission means affording extremely easy operation and which cooperates to instantaneously lock the window in a desired position upon movement into such position.

It is, therefore, the primary object of the present invention to provide a new and improved operator for opening and closing casement windows.

Another object is to provide an operator which can be installed easily on presently existing casement window constructions.

A further object is to provide a casement window operator which is capable of adjusting the window to any desired position in its swingable path and immediately and automatically locking the window in such position until further manual operation of the operator.

A still further object is to provide an operator which is compact and is capable of applying a superior degree of mechanical advantage in opening and closing the window.

A still further object is to provide an operator having an extendible tongue member for applying a pushing force to said window, the tongue member proceeding in a straight path and the operator having structure to compensate for the relative movement of the swinging window and the linear movement of the tongue member.

Other objects, features, and advantages of the present invention will be apparent from the following illustration of a preferred embodiment in the accompanying drawings in which:

FIGURE 1 is a broken plan view partly in section of the window operator embodying my invention as installed on a casement window construction shown in section; the window and connected portion of the operator being also shown in an intermediate open position of the window in broken outline;

FIGURE 2 is a broken sectional view of the window hinge taken substantially as indicated along line 2—2 of FIGURE 1;

FIGURE 3 is an exploded perspective view of the connector which joins the extendible tongue member of the operator to the fixed window bracket;

FIGURE 4 is a fragmentary plan view of the outer end of the tongue member removed from the assembly;

2

FIGURE 5 is a sectional view of the tongue member taken substantially as indicated along 5—5 of FIGURE 4;

5 FIGURE 6 is a view similar to FIGURE 1 showing the window and operator in the fully opened position of the window;

FIGURE 7 is a vertical sectional view through the window and the operator taken substantially as indicated along line 7—7 of FIGURE 1; and

FIGURE 8 is a vertical sectional view through the window and the operator taken substantially as indicated along line 8—8 of FIGURE 1.

Referring now to the drawings and more particularly to FIGURES 1 and 6, there is shown a preferred embodiment of the present invention adapted to operate a presently existing double-pane casement window 10 having a sash 11 composed of inner and outer sash elements 12 and 13 constructed to hold glass panes 14 in a well known manner. The window is swingably supported on 10 hinges 15 having a vertical pivotal axis and pin 16 spaced from the sash 11. The hinges 15 have upper and lower hinge plates 17 and 18 movable in parallel planes; upper hinge plate 17 has upturned flange 19 attached to the outer vertical face of the sash 13 and hinge plate 18 20 has slightly bent end 20 attached to an upwardly facing step of the window framework 42 facing the sash. The window sash swings open in a direction indicated by arrow 38.

Most casement window constructions employ hinges 30 similar to those illustrated in FIGURES 1 and 2 in order to properly bring the sash into its frame. In the present wood sash and frame construction, the joining surfaces are rabbeted as shown, and the outside hinge axis swings the sash so that the rabbets come together as illustrated in full lines in FIGURE 1. The operator of 35 of the present invention is intended to occupy a fixed position relative to the frame and accommodate the swing of the sash required by the particular hinge structure and location of the pivot axis.

The window operator of this invention employs a 40 linearly movable tongue member connected to the sash outwardly along the sash from the side connected to the hinges. The tongue member 21 is connected to the window sash 11 by a connector comprising a number of parts and generally designated 22, permitting the tongue member to proceed in a linear path for pushing or pulling the window sash in its swinging path. The tongue member is moved along its path by a driving means supported in housing 24 attached to the window framework 42.

50 The specific parts of the connector 22 include a link 26, pivot pins 27 and 28, a stop member 29, and a window bracket 25 attached to the window sash. The window bracket 25 has an upwardly extending leg 30 fastened to the inside vertical face of the sash 11 and a horizontally extending leg 31 with an upper face 32 in the plane of the upper surface of the tongue member. A first end 33 of a link 26 is pivotally connected to the window bracket by pivot pin 27 extending through an opening in leg 31 and opposite end 35 is pivotally connected to the tongue member by pivot pin 28 extending through opening 36 in the end of the tongue member. The link 26 lays in a plane generally parallel to the upper face of leg 31 of the bracket and may swing in this plane as the window sash is moved. The stop member 29 is 55 pivotally connected by pin 40 to an intermediate portion of the link and engageable with a flange 41 extending upward from and perpendicular to an intermediate portion of the link.

When the tongue member is moved linearly in its 60 path to open the window (indicated by arrow 37), it applies a force through connector 22 and the window

bracket to swing the sash 11 and the bracket along a curved path (indicated by arrow 38). Link 26 is caused to pivot simultaneously about both pivot pins to compensate for the relative movement between the bracket and end of the tongue member as illustrated by the various positions shown in FIGS. 1 and 6. To prevent the link from assuming too great an angle with respect to the path of the tongue member when it is near or at the closed-window position, the stop member 29 is provided with sufficient length to be engaged by the bracket 25 on the window sash. At the closed-window position, the stop member abuts or engages flange 41 and prevents the link 26 from further pivoting. Pivot pins 27 and 28 may be sufficiently loose within the respective openings through the window bracket, link, and tongue member to allow the stop member to take up the looseness and assume the major beginning opening thrust from the tongue to the sash. Stop member 29 serves to limit the inward movement of the tongue member and the angular movement of the link, as well as serving as a primary thrust member leading from the tongue member when initially pushing the window out of the frame.

Tongue member 21 has an opening 43 to permit reversibility of the connector when used with an oppositely opening casement window; flange 44 of the link permits the stop member to reverse its operation when the connector is so reversed.

The tongue member is constructed of flexible spring metal having a transverse arch (FIG. 5) to give longitudinal rigidity when extended outward along its path in order to transmit sufficient pushing or pulling force when opening or closing the window sash. Perforations 45 are longitudinally aligned along the length of the tongue member adapted to receive the projections 46 of a sprocket wheel 47 mounted in the housing 24. A bottom plate 58 of the housing is adjacent to the periphery of the sprocket wheel permitting the tongue member to pass therebetween only when the projections on the sprocket wheel are inserted in the perforations of the tongue member. The bottom plate acts as a back stop to hold the tongue member against the sprocket wheel and insure that the projections 46 enter the perforations and drive the tongue member.

The sprocket wheel 47 is a part of the driving means which also includes a hand crank 48 and an intervening transmission. The transmission (FIGS. 7 and 8) includes a drive shaft 49 rotatably mounting the sprocket wheel, a spool 50 unattached to the tongue member, but about which the flexible tongue member may wind into a compact space, a shaft 51 rotatably mounting the spool, a small spur gear 52 fixedly mounted on the drive shaft 49, a large spur gear 53 fixedly mounted on the spool shaft in mesh with small spur gear 52, and a worm gear 54 extending along a portion of the hand crank and in mesh with the large spur gear 53 on the spool shaft.

The housing 24 encloses the transmission and that portion of the tongue member wound about the spool and rotatably supports the drive shaft 49, the spool shaft 51, and the hand crank 48. The housing 24 is attached to the window framework 42 by an extension of the bottom of the housing forming a plate portion 55 secured to a step of the framework facing the sash and by a plate 56 secured to the inside vertical face of the framework. A web 57 extends beneath the housing to add strength to the housing bottom and attaching plates.

To open the casement window, an operator merely turns the hand crank 48 which draws tongue member 21 from the spool to extend it directly toward the window along a straight path. The turning motion is transmitted to the tongue member through the transmission previously described.

As the tongue member initially proceeds along its path the stop member 29 is in engagement with the window-sash and acts as the primary thrust element to start opening the window. The link 26 is caused to pivot about

both of its ends to maintain the connection between the window sash and tongue member while accommodating the relative movement therebetween. After the window sash has moved away from contact with the stop member, pins 27 and 28 solely transmit the pushing or pulling force to window bracket. In the fully open position of the window, the tongue member is parallel and adjacent to the inner vertical face of the window sash. It is important to proper functioning of the operator that it be mounted on the window framework, spaced from the hinges so that the window sash and tongue member are parallel at the final open position. This relationship permits a ready guide to initial installation of the operator on a window frame.

To close the window the operator turns the crank in the opposite direction whereby the tongue is drawn in by the sprocket wheel. Near to its closing position the window sash engages the stop member which in turn is caused to engage flange 41 at the exact closed position to prevent link 26 from pivoting further.

Upon adjusting the window sash to a desired position, the sash becomes instantly locked by the driving means until further manual operation due to the friction in the transmission. The described operator is compact by virtue of its coillable tongue member and can be mounted as easily as any other hardware without special space requirements. Also the described transmission affords a superior degree of effortless operation.

The foregoing detailed description has been given for clearness of understanding only, and no unnecessary limitations should be understood therefrom, for some modifications will be obvious to those skilled in the art.

I claim:

1. A casement window operator for opening and closing a casement window swingably supported to move in a horizontal path about an upright pivot axis, comprising: a flexible longitudinally extending tongue member transversely arched to give sufficient longitudinal rigidity for applying a force capable of opening said casement window; a bracket fixedly attached to a portion of said casement window; a link having a first end pivotally connected to the end of said tongue member about a first axis and its opposite end pivotally connected to said bracket about an axis spaced from said first axis, said link simultaneously pivoting about both axes to permit relative movement between the widow as it proceeds in a horizontally swinging path and the end of said tongue member as it proceeds in a straight path, said link having a flange extending upwardly intermediate said first and opposite ends; a stop member pivotally connected to said link intermediate said first and opposite ends, said stop member being engageable by said casement window causing said stop member to abuttingly engage said flange on said link and prevent said link from pivoting; and a drive means to feed said tongue member along a straight path for opening said window and to retire said tongue member into a compact space when closing the window.

2. A casement window operator for opening and closing a casement window swingably supported to move in a horizontal path about an upright pivot axis, comprising: an extendible flexible and coillable tongue member transversely arched to give sufficient longitudinal rigidity for applying a force capable of opening said casement window, said tongue member having longitudinally aligned perforations substantially throughout its length; a rotatable sprocket wheel having projections on its outer rim for driving engagement with perforations of said tongue member; a bracket fixedly attached to a portion of said casement window; a link having a first end pivotally connected to the end of said tongue member about a first axis and its opposite end connected to said bracket about an axis spaced from said first axis, said link simultaneously pivoting about both axes permitting relative movement between the window as it proceeds in a horizontally swinging path and the end of said tongue member as it

proceeds in a straight path, said link having a flange intermediate said first and opposite ends extending perpendicular thereto for engaging a stop member, said stop member engageable by said casement window causing said stop member to abuttingly engage said flange on said link and prevent said link from pivoting, said stop member in cooperation with said link aiding to transmit force to the window bracket during the initial stages of opening said casement window; a drive shaft rotatably mounting said sprocket wheel; a spool for coiling up said extendible tongue member into a compact space; a shaft rotatably mounting said spool; a spur gear fixedly mounted on said drive shaft; a spur gear fixedly mounted on said spool shaft in mesh with said spur gear on said drive shaft; a hand operated crank having a worm gear along a portion of its length in mesh with the spur gear on said spool shaft; and a housing rotatably supporting

10

5 the housing includes a bottom plate adjacent to the periphery of said sprocket wheel permitting said tongue member to pass therebetween only when the projections on said sprocket wheel are inserted in the perforations of said tongue member.

said drive shaft, spool shaft and crank, said housing adapted to be attached to a presently existing casement window construction.

3. A casement window operator as in claim 2, in which

5 the housing includes a bottom plate adjacent to the periphery of said sprocket wheel permitting said tongue member to pass therebetween only when the projections on said sprocket wheel are inserted in the perforations of said tongue member.
